UNITED STATES PATENT OFFICE.

JOHN G. ROBINSON, OF MELROSE, MASSACHUSETTS.

GENERATION OF POWER.

1,186,946.

Specification of Letters Patent. Patented June 13, 1916.

Application filed October 16, 1915. Serial No. 56,311.

To all whom it may concern:

Be it known that I, JOHN G. ROBINSON, a citizen of the United States, and a resident of Melrose, in the county of Middlesex and 5 State of Massachusetts, have invented a new and useful Improvement in Generation of Power, of which the following is a specification.

My invention relates to the generation of 10 power and more particularly to systems of power generation whereby a stream of water is caused to flow continuously through a system of piping by atmospheric pressure acting against a vacuum created by the condensation of steam, said stream of water 15 operating a turbine or other energy-translating device.

The object of my invention, which is an improvement on the system shown in my 20 application Serial No. 838,572 filed May 14, 1914, is to provide means whereby the energy of steam may be converted into the energy of motion by means of a simple apparatus that can be economically constructed 25 and operated, and to improve and simplify the system shown in said application by eliminating the lower reservoir which is connected with the steam vacuum pump, and otherwise to improve the same.

30 The principle of my invention will be explained by reference to the accompanying drawings, which illustrate a simple embodiment thereof, but it will be understood that various modifications may be made in the 35 apparatus itself and in the arrangement of the parts thereof without departing from my invention, the scope of which is defined in the appended claims.

Figure 1 is an elevation of my improved 40 system, certain parts being shown in section. Fig. 2 is a side view of one of the valve operating disks, and Fig. 3 is a vertical section of said disk.

In the particular drawings selected for 45 explaining the principle of my invention, 1, 2, 3 represent tanks, shown in the present instance as three in number, although in practice I prefer to employ a larger number. In order to obtain practical continuity 50 of flow through a system of piping, I believe that no fewer than three tanks should be employed. It will be understood of course that I do not limit myself as to the number of tanks and that when more than three are 55 used they are preferably arranged with their centers equidistant from a fixed point as

shown in my earlier application above referred to. Each tank is connected with a pipe 4 which leads to a source of steam supply (not shown) a water inlet pipe 6, 6', 60 6'' and a water outlet pipe 7, 7', 7'', the three sets of pipes being connected to such portions of each tank as may best enable them to perform their respective functions. A system of piping comprising the pipes 8, 65 9, herein shown as horizontal, is connected with the water inlet and outlet pipes, the inlet pipes being connected with the portion 8 of said system and the outlet pipes with the portion 9 thereof, and in any convenient 70 part of said system an energy translating device such as a turbine or water wheel 10 is placed so as to be actuated by the stream of water circulating through said system.

Each water inlet pipe is provided with 75 an upwardly opening valve 11, 11', 11'', said valves normally being held to their respective seats by a spring, and similar downwardly opening valves 12, 12', 12'' are placed in the water outlet pipes. Each tank 80 is provided with a vacuum breaking valve 13, 13', 13'', such valves being shown in the present instance as placed in the top of each tank, and also with an air outlet valve 14, 14', 14'', each of which may be 85 placed in any suitable part of a tank. Each branch of the steam pipe 4, which connects with the tanks is controlled by a valve which is operated by a lever 5, 5', 5''.

It will be understood of course that numerous arrangements of mechanism may be employed to control the vacuum breaking air and steam valves, and in the present instance I have shown a simple mechanism that may be employed for this purpose, 90 without of course limiting myself thereto. The upright shaft 15 operatively connected with the turbine transmits motion to the horizontal shaft 16 by means of the worm and gear 17, 18, and on the last mentioned 100 shaft may be secured various devices for communicating motion to the valves in question. In the present instance, disks 19, 19', 19'', each face of which is provided with a cam groove 20, are rotated continuously by said shaft and valve stems 21, 21', 21'', and 22, 22', 22'', connect the vacuum breaking and air valves respectively to said cam grooves, whereby at the proper time the said valves will be seated and unseated. 105 Similar disks 23 may be employed for controlling the steam valves, a cam groove in 110

each of said disks coöperating with the rods 24, 24', 24'' which are connected with slots at the ends of the levers 5, 5', 5'', respectively.

It is desirable that the shaft 16 should 5 rotate very slowly and for this purpose it is understood of course that a variety of speed-reducing connections may be interposed between said shaft and the vertical shaft 15, the particular connection shown 10 in the drawings, namely a worm and gear, being merely illustrative. It will also be understood that where the tanks are arranged with their centers equidistant from a common center as shown in my application above referred to, the valve operating 15 mechanism will be appropriately modified and that the mechanism shown in said application may with slight modification be used. The surplus power developed 20 by the turbine may be utilized by means of suitable connections with the shaft 15.

The operation is as follows: Assuming that the several parts have the positions shown in Fig. 1, steam will enter tank 1 25 through the valve controlled by the lever 5 and will expel the air therefrom through the valve 14, whereupon the steam valve and air outlet valve will both be closed, the steam will be caused to condense by any of 30 the usual well known means employed in steam vacuum pumps, for example, the water jacket 25, and a vacuum will be formed in said tank. At the same time, a 35 vacuum having been formed in tank 3, water is drawn up into said tank through the inlet pipe 6'' past the valve 11'', which by virtue of said vacuum is raised from its seat. As soon as the tank is filled or 40 partially filled, the vacuum is broken and the tank emptied. Tank 2 shows the position of 45 the valves when the vacuum has been broken by the unseating of the valve 13'. The breaking of the vacuum causes the seating of the valve 11' and the unseating of the valve 12', the latter of course being assisted by the weight of the water in the tank, which by the action of gravity flows through 50 the outlet pipe 7' and into the portion 9 of the system of piping. It will be noted that the passage of water from the tank 2 into the pipe 9 is assisted by the vacuum created in tank 3.

From the foregoing it will be obvious that 55 at any moment at least one tank is filling with water, another is emptying, and the third is being filled with steam, so that at any period in the operation of the system a vacuum in one tank is drawing water out of another and up into itself, whereby there

results a continuous flow of water through 60 the piping 8, 9 with which the turbine 10 is associated.

The amount of water originally placed in the system must of course be determined experimentally and will depend upon the number of tanks employed. There should, however, be enough at least to fill one tank, the system of piping 8, 9 and one water inlet pipe.

By means of the present invention, no 70 lower reservoir such as heretofore employed with steam vacuum pump systems is required, and a considerable economy of space as well as increased efficiency in operation are secured.

Having thus described one illustrative embodiment of my invention, without however limiting the same thereto except as specified in the following claims, what I claim as new and desire to secure by Letters 75 Patent is—

1. The combination with a steam vacuum pump of an energy translating device and a closed system of piping connecting said device with said pump.

2. The combination with a steam vacuum pump of an energy translating device, means operated by said device for controlling said pump and a closed system of piping connecting said device with said 90 pump.

3. In combination, a plurality of tanks, a closed system of piping, inlet pipes connecting each tank with one branch of said system of piping, outlet pipes connecting 95 each tank with the other branch of said system of piping, means for admitting steam to said tanks successively, and an energy translating device operatively connected with said system of piping.

4. In combination, a plurality of tanks, a closed system of piping, inlet pipes connecting each tank with one branch of said system of piping, outlet pipes connecting each tank with the other branch of said 105 system of piping, means for admitting steam to said tanks successively, an energy translating device operatively connected with said system of piping, and means actuated by said device for controlling the admission of steam to said tanks.

In testimony whereof, I have hereunto subscribed my name this 15th day of October, 1915.

JOHN G. ROBINSON.
